FIG. 6.

UNITED STATES PATENT OFFICE.

STEPHEN POKOPAC, OF GREENSBURG, PENNSYLVANIA.

MOVABLE RAILWAY PLATFORM OR APPROACH.

1,235,377.

Specification of Letters Patent. Patented July 31, 1917.

Application filed April 30, 1917. Serial No. 165,416.

To all whom it may concern:

Be it known that I, STEPHEN POKOPAC, a subject of the King of Hungary, residing at Greensburg, in the county of Westmoreland and State of Pennsylvania, have invented certain new and useful Improvements in Movable Railway Platforms or Approaches, of which the following is a specification.

10 This invention relates to certain new and useful improvements in movable railway platform approaches.

The primary object of the invention is the provision of a loading platform for use in 15 connection with railway cars, the same being readily movable adjacent the cars and serviceable as a baggage or passenger station.

A further object of the device is the provision of a movable platform or station arranged adjacent a railroad track whereby 20 the station may be readily connected with the cars upon the track for facilitating the transfer of passengers and goods between the station and cars.

25 A still further object of the device is the provision of a station platform provided with motive power for moving the same in operative position with respect to railway cars, approach members being readily arranged, connecting the platform and cars, assisting in the loading and unloading operation.

In the drawings forming a part of this application and in which like designating 35 characters refer to corresponding parts throughout the several views:—

Figure 1 is a side elevation of a railway car adapted to be employed in connection with the present device.

40 Fig. 2 is a top plan view of a portion of a train and illustrating the device operatively arranged with respect thereto.

Fig. 3 is an end elevation of the car and track shown in Fig. 1.

45 Fig. 4 is an end elevation of the device and one of the cars shown in Fig. 2, with the approaches and connectors retracted.

Fig. 5 is a view similar to Fig. 4 with the connectors and approaches operatively arranged.

50 Fig. 6 is a horizontal sectional view taken through the device.

Fig. 7 is a side elevation thereof.

Fig. 8 is a detail sectional view taken upon line VIII—VIII of Fig. 6. 55

Fig. 9 is a vertical transverse sectional view taken upon line IX—IX of Fig. 7.

Fig. 10 is an enlarged detail sectional view taken upon line X—X of Fig. 6.

Fig. 11 is an enlarged detail view of a 60 central portion of the movable connecting means.

Fig. 12 is a perspective view of one of the car carried keeper blocks, and,

Fig. 13 is a perspective view of an end 65 portion of one of the adjustable approaches.

The present invention broadly contemplates the provision of a movable station or covered platform 10 mounted upon a track 11 paralleling the track 12 of the railway 70 line upon which the cars 13 are operated, it being understood that both freight and passenger cars are employed while the present showing is that of passenger cars.

The platform or station 10 has the general form of a railway car having one side 14, a roof 15 and opposite ends 16, the side of the car which is positioned adjacent the line of railway tracks 12 being preferably open as shown in Figs. 8 and 9. Suitable 80 windows 18 are provided in the ends 16 as well as in the side 14 of the platform 10 while doors 19 are arranged adjacent the ends thereof and a relatively large or freight receiving door 20 is centrally positioned in 85 the said side. Suitable steps 21 are provided for the doors 19 for permitting the ready entrance of passengers to the platform 10 whereby the same is employed as

and is substantially of the form of the usual 90 track side shelters or stations especially serviceable in outlying districts. The platform 10 may be provided with motive power from suitable batteries 22 operable by means of a controller 23. An approach or plank 95 24 is provided at different desirable points upon the platform 10, such as adjacent the opposite ends thereof, the approaches 24 being herein illustrated as adapted to be projected upon the end platforms 25 of the cars 100 13. The approaches 24 are positioned beneath the floor 26 of the platform 10 and are arranged with teeth 27 forming a rack with which a pinion 28 is in constant mesh, the said pinion being provided upon a shaft 105 29 journaled beneath the floor 26. Any suit-

able operating means may be provided for the shaft 29 such as a sprocket wheel 30 carried thereby, having a chain 31 passing thereover for engagement with a double sprocket 32 operable from a hand wheel 33 by means of a chain 34 connecting the said double sprocket and hand wheel. By this arrangement it will be seen that when the car 13 reaches the proper position adjacent to the platform 10, the hand wheels 33 may be turned for projecting the approaches 24 upon the platforms 25 of the car, whereby passengers as well as goods may be readily transferred from one to the other.

15 A means is provided for readily connecting the platform 10 with the car 13, whereby the platform may be readily moved upon the track 11 by means of the railway car, such connections broadly consisting of 20 keeper blocks 35 secured at spaced intervals beneath the body of the car and adapted for coöperation with a shiftable connector 36 arranged upon the platform 10. The connector 36 consists of parallel trans- 25 verse members 37 and a connecting piece 38, the entire connector 36 being slidably arranged beneath the floor 26 of the platform 10. A central transverse member 37 has its inner end provided with a slot 39 30 adapted for the reception of the lower end of an operating lever 40 pivoted to posts 41 upon the platform floor 26 and having a handle 42. By grasping the handle 42, the lever 40 may be pivotally moved 35 through the slot 43 in the floor 26, thereby shifting the member 36 inwardly or outwardly as desired. When the coupling member 36 is projected, the outer portions of the transverse members 37 project later- 40 ally of the platform 10 sufficiently to be placed within the line of movements of the keeper blocks 35. The transverse members 37 being received within the adjacent side channels 44 of the blocks 35, it will be un- 45 derstood that a movement of the car 13 will simultaneously move the platform 10 in a corresponding direction and whereby the said platform may be shifted upon its track 11 to any desirable point, the platform 10 50 being at all times maintained suitably spaced from the line tracks 12 so as to be accessible from the cars 13 mounted thereon. It will be seen that a serviceable platform in the nature of a shelter is arranged for

advantageous use by railroads, the device 55 readily serving as a small railway station when found desirable.

What I claim as new is:—

1. A device of the class described comprising a movable platform having a roof, 60 ends and one partially closed longitudinal side, the opposite side of the platform being open, a car connector carried by said platform laterally projecting therefrom when projected in its operative position, 65 and shifting means for said connector arranged within the device.

2. A device of the class described comprising a movable platform having a roof, 70 ends and one partially closed longitudinal side, the opposite side of the platform being open, a car connector carried by said platform laterally projecting therefrom when projected in its operative position, shifting 75 means for said connector arranged within the device, approaching planks transversely shiftably carried by the said platform adapted for arrangement outwardly of the open side of the latter when operatively positioned, and operating means for the said 80 planks.

3. A device of the class described comprising in combination with parallel main and side tracks having cars adapted for movement upon one line of tracks, a platform adapted for movement upon the other track, ends, a top and one side provided for the said platform with the side thereof open adjacent the main track, a car connecting means shiftably carried by the said 85 platform, and operating means for the said connecting means.

4. A device of the class described comprising in combination with parallel main and side tracks having cars adapted for 90 movement upon one line of tracks, a platform adapted for movement upon the other track, ends, a top and one side provided for the said platform with the side thereof open adjacent the main track, a car connecting 95 means shiftably carried by the said platform, operating means for the said connecting means, cars upon said main track, and keeper blocks carried by the said cars having a path of movement within the plane 100 of said connector when projected.

In testimony whereof I affix my signature.

STEPHEN POKOPAC.
